UNITED STATES PATENT OFFICE

133,957

DESIGN FOR AN ENGINE STAND

Lawrence W. Alfred, Denver, Colo.

Application August 19, 1942, Serial No. 107,962

Term of patent 3½ years

To all whom it may concern:

Be it known that I, Lawrence W. Alfred, an employee of the United States Government, a citizen of the United States, residing at Denver, Colorado, have invented a new, original, and ornamental Design for an Engine Stand, of which the following is a specification, reference being had to the accompanying drawing, forming part thereof.

The single view of the drawing is a perspective view of an engine stand, showing my new design.

I claim:

The ornamental design for an engine stand, as shown.

LAWRENCE W. ALFRED.
